UNITED STATES PATENT OFFICE.

JOHN W. JEPSON, OF DEPEW, NEW YORK, ASSIGNOR TO GOULD COUPLER COMPANY, A CORPORATION OF NEW YORK.

LIGHTING SYSTEM.

1,236,180.

Specification of Letters Patent. Patented Aug. 7, 1917.

Application filed February 28, 1914. Serial No. 821,774.

To all whom it may concern:

Be it known that I, JOHN W. JEPSON, a citizen of the United States, and a resident of Depew, Erie county, New York, have invented certain new and useful Improvements in Lighting Systems, of which the following is a specification.

My invention relates to lighting systems and more particularly to lighting systems for electric motive power cars, that is, cars driven by electric motive power supplied by a feeder such as a third rail or trolley from a power station. My improvements are especially applicable to electric motive power cars which in their use are not only at times driven by electric motive power, but which are at other times propelled by other power, as a steam locomotive.

One object of the invention is to provide a simple and efficient system in which a storage battery is adapted to supply energy to light the car when it is not supplied with energy from the motive power feeders. A further object of the invention is to provide a system of this sort in which a storage battery may be properly charged from energy supplied from the motive power mains or feeders. Further objects, features and advantages will more clearly appear from the detailed description given below taken in connection with the accompanying drawing which forms a part of this specification and which illustrates diagrammatically a system which embodies my improvements in one form.

Referring to the drawing, 1 represents a motive power feeder which may be either a third rail or trolley, and 2 represents the lamps or lights of the car which are adapted to be connected between the feeder 1 and ground 3 by the closing of a double pole switch 4, the circuit being from the feeder 1 through lamps 2, conductor 5, left hand side of double pole switch 4, conductor 6, magnet coil 7, right-hand side of double pole switch 4 and conductor 8 to ground.

9 represents a storage battery also adapted to be connected in shunt between the main 1 and ground, but having in series therewith a switch 10 and fixed resistance 11. When the switch 10 is closed energy is supplied from the main feeder 1 through the resistance 11 to charge the battery 9 in a manner well understood by those skilled in

the art. Connected in shunt across the terminals of the battery 9 is an auxiliary lighting circuit 12 feeding auxiliary lights 13, the connections from the battery to this circuit being through conductor 14, lighting circuit 12, solenoid coil 15, conductor 16, 60 switch 17, righthand side of double pole switch 4 and conductor 8, back to the opposite side of the battery.

The magnet 7 is adapted to operate the switch 17 to open the same when current flows through the coil 7 and the main lights 2. The switch 10 is provided with a fixed contact 18 and movable contact 19 which are adapted to engage one another upon the closing of the switch prior to the engagement of contacts 20 and 21 of the switch to prevent injurious sparking. The movable contacts 19 and 21 are secured to a pivoted arm 22 pivoted at 23 and carrying a solenoid plunger 24 operated by the solenoid coil 15. The arm 22 is also provided with a catch 25 adapted to engage with a catch 26 pivoted at 27 and having rigidly secured thereto a lateral arm 28 adapted to be engaged by the core 29 of a solenoid 30, the terminals of which solenoid are connected directly across the battery by means of conductors 31 and 32. 33 represents a stop for the plunger 29. The switch contacts 19 and 21 are electrically connected with the positive terminal of the battery by means of a conductor 34.

In operation, with the car operating under electric motive power supplied from the feeder 1, and it being desired that the car 90 be lighted, the switch 4 is closed thereby permitting the lights 2 to be energized by energy supplied from the main 1, as above described. If the battery be not fully charged the charging current will also be 95 supplied thereto from the main 1 through the resistance 11, contacts 18 and 20 to contacts 19 and 21 of the switch 10, through conductor 34 and conductor 14 to the battery line, thence by conductor 8 to the ground 3 100 which acts as a return main or feeder.

Under these conditions with the lights 2 energized by energy received from the main 1 the magnet 7 will attract the armature of the switch 17 and thus open the auxiliary 105 lighting circuit so that the lights 13 will not be connected in circuit and the solenoid 15 will be deenergized. The core 24 of the sole-

noid will, however, be held in its upper position to close the switch 10 because of the engagement of the catch 25 with the catch 26. When the battery becomes sufficiently charged as evidenced by its rise in voltage the strength of the solenoid 30 will be sufficient to raise its core and cause it to hit or engage the arm 28, thus moving the same about its pivot 27 and causing the catch 26 to be disengaged from the catch 25 so that the core 24 will drop by gravity and thus open the switch 10, thereby discontinuing the charging current to the battery 9. If now the energy supplied from the rail 1 should fail for any reason as by the car being drawn by other power at a place where no supply feeder exists, then the current through the lights 2 and magnet 7 will fail, permitting the armature switch 17 to drop by gravity and close the switch so as to connect the auxiliary lighting circuit 12 across the battery 9 whereby the car will be lighted from the auxiliary lights 13. This will mean that energy will be taken from the battery to light the car and accordingly it will be desirable to connect the battery in shunt between the main 1 and ground again so that it will be ready to receive charging current as soon as the car shall be again in position to make connection with the motive power feeder. This is accomplished as follows:

Upon the closing of the switch 17 which causes the lighting circuit 12 to be energized from the battery the solenoid coil 15 is at the same time energized, thereby raising its core so as to close the switch 10, and at the same time the catch 25 reengages the catch 26 as soon as the voltage of the battery drops sufficiently under discharge to cause the core 29 of solenoid 30 to drop to permit the catch 26 to swing into engagement with the catch 25.

Although I have described my improvement in great detail and with respect to one particular form thereof it will be understood that I do not desire to be limited to the details as shown and described, except as specifically set out in the appended claims since many changes and modifications may well be made without departing from the spirit and scope of my invention in its broader aspects.

Having fully and clearly described my improvements, what I claim as new and desire to secure by Letters Patent is:

1. A lighting system for cars adapted to be electrically propelled, having a feeder furnishing electric energy to the car or cars for motive power, a series of lamps or lights in the car or cars connected in shunt across said feeder and ground, a storage battery and a resistance in series therewith also connected in shunt across said feeder and ground, whereby the battery may be charged by the feeder, an auxiliary light circuit hav-

ing auxiliary lights therein connected across the battery, a switch in the auxiliary light circuit, an electroresponsive device adapted to cause said switch to close the auxiliary light circuit upon a failure of current from the feeder, and means for automatically disconnecting the battery from the feeder upon the battery becoming substantially charged. 70

2. A lighting system for cars adapted to be electrically propelled, having a feeder furnishing electric energy to the car or cars for motive power, a series of lamps or lights in the car or cars connected in shunt across said feeder and ground, a storage battery and a resistance in series therewith also connected in shunt across said feeder and ground whereby the battery may be charged by the feeder, an auxiliary light circuit having auxiliary lights therein connected across the battery, a switch in the auxiliary light circuit, an electroresponsive device adapted to cause said switch to close the auxiliary light circuit upon a failure of current from the feeder, means for automatically disconnecting the battery from the feeder upon the battery becoming substantially charged, and means for automatically connecting the battery to the feeder upon the energization of the auxiliary light circuit should the battery then be disconnected therefrom. 95

3. A lighting system for electric motive power cars, having in combination with the car, lights connected in shunt across the motive power, a storage battery connected in a separate shunt circuit across the motive power mains to be charged thereby, means for automatically disconnecting the storage battery from the mains when it has become substantially charged, and auxiliary lights adapted to be energized from the storage battery upon the failure of energy from the motive power mains. 100

4. A lighting system for electric motive power cars having in combination with the car, lights connected in shunt across the motive power, a storage battery connected in a separate shunt circuit across the motive power mains to be charged thereby, means for automatically disconnecting the storage battery from the mains when it has become substantially charged, an auxiliary lighting circuit connected across the storage battery, and means for closing said auxiliary circuit upon the failure of energy from the motive power mains. 110

5. A lighting system for electric motive power cars having in combination with the car, lights connected in shunt across the motive power, a storage battery connected in a separate shunt circuit across the motive power mains to be charged thereby, means for automatically disconnecting the storage battery from the mains when it has become substantially charged, auxiliary lights adapted to be energized from the storage battery 125

upon the failure of energy from the motive power mains, and means responsive to the energization of said auxiliary lights for automatically connecting the battery across 5 the mains.

6. A lighting system for electric motive power cars having in combination with the car, lights connected in shunt across the motive power, a storage battery connected 10 in a separate shunt circuit across the motive power mains to be charged thereby, means for automatically disconnecting the storage battery from the mains when it has become substantially charged, an auxiliary lighting 15 circuit connected across the storage battery, means for closing said auxiliary circuit upon the failure of energy from the motive power mains, and means for automatically connecting the battery across the mains when 20 the auxiliary lighting circuit is connected across the battery.

7. A lighting system having in combination a series of lights supplied from suitable mains, a storage battery connected to be 25 charged from said mains, auxiliary lights connected to be supplied by the battery upon failure of said mains to supply said first mentioned lights, and means for automatically stopping the battery charging when it 30 becomes substantially charged.

8. A lighting system for electric motive power cars having in combination a series of car lights supplied from the motive power mains, a storage battery also connected to 35 be charged from the motive power mains, and auxiliary lights, means for automatically connecting the auxiliary lights to be fed by the battery upon a failure of energy from the motive power mains, and means 40 for automatically disconnecting the storage battery when it has become substantially charged.

9. A lighting system for cars having in combination a series of car lights supplied 45 from suitable mains, a storage battery also connected to be charged from the said mains, means whereby the car may be lighted by energy taken from the battery upon a failure of energy from the said mains, and 50 means for automatically disconnecting the storage battery when it has become substantially charged and automatically connecting it in circuit with the supply mains upon failure of potential therein from their source.

55 10. A lighting system for electric motive power cars having in combination a series of car lights supplied from the motive power mains, a storage battery also connected to be charged from the motive power mains, 60 means whereby the car may be lighted by energy taken from the battery upon a failure of energy from the motive power mains, and means for automatically connecting the battery across the motive power mains when 65 the car is lighted from the battery.

11. A lighting system for electric motive power cars having in combination a series of car lights supplied from the motive power mains, a storage battery also connected to be charged from the motive power mains, 70 means whereby the car may be lighted by energy taken from the battery upon a failure of energy from the motive power mains, means for automatically connecting the battery across the motive power mains when 75 the car is lighted from the battery, and means for automatically disconnecting the storage battery when it has become substantially charged.

12. A lighting system for electric motive power cars, having in combination a series of car lights supplied from the motive power mains, a storage battery also connected to be charged from the motive power mains and auxiliary lighting circuit, means for automatically connecting the auxiliary lighting circuit across the battery on failure of energy from the motive power mains, means for disconnecting the battery from the motive power mains when substantially 90 charged, said means including a switch in circuit with the battery, means for closing said switch upon the energization of the auxiliary lighting circuit, and means for holding said switch closed by the deenergization of the auxiliary lighting circuit until 95 the battery has become substantially charged.

13. A lighting system for electric motive power cars having in combination with the car and motive power mains, regular lights 100 connected to be supplied from the motive power mains, a storage battery connected to be charged from the motive power mains, means preventing overcharge of the battery when it has become substantially charged, 105 an auxiliary light circuit, an electro-responsive switch for automatically connecting the auxiliary light circuit across the battery to be supplied therefrom, and means for simultaneously disconnecting the main lights 110 from the motive power mains and opening the auxiliary light circuit to the battery, and vice versa.

14. A lighting system for electric motive power cars having in combination with the car and motive power mains, regular lights connected to be supplied from the motive power mains, a storage battery connected to be charged from the motive power mains, 115 means preventing overcharge of the battery when it has become substantially charged, an auxiliary light circuit, an electro-responsive switch for automatically connecting the auxiliary light circuit across the battery to be supplied therefrom, and means for disconnecting said electro-responsive switch and opening the circuit between the battery and auxiliary lights. 120

15. A lighting system for electric motive power cars having in combination with the 130

- 4
- car and motive power mains, regular lights connected to be supplied from the motive power mains, a storage battery connected to be charged from the motive power mains,
  - 5 automatic means connecting the battery to the supply mains to be charged, an auxiliary light circuit connected across the battery, a switch for opening and closing said auxiliary light circuit, electro-responsive means
  - 10 for opening said switch when the main lights are energized and a hand switch for

simultaneously opening the auxiliary light circuit and disconnecting said electro-responsive means and vice versa.

In testimony whereof, I have signed my 15 name to this specification, in the presence of two subscribing witnesses.

JOHN W. JEPSON.
